UNITED STATES PATENT OFFICE

JOHN J. GAULT, OF CHICAGO, ILLINOIS, ASSIGNOR TO W. J. NEWMAN COMPANY, OF CHICAGO, ILLINOIS

EXCAVATING BUCKET

Application filed July 8, 1929. Serial No. 376,601.

This invention relates to excavating buckets of the type having more than two jaws or sections, some of the buckets of this character being commonly known as orange peel buckets or "four arm buckets." When such ordinary four arm buckets are opened, the points of the blades are spread to such an extent that if the bucket is dropped there is more or less of a spring or resilient action in the blades due to the force of the weight at the center, which prevents the blades from being driven into the ground or material to be excavated. Furthermore, the arrangement of these blades as ordinarily made is such that there is a tendency for them to bend at a short distance from the ends which is due to the low or flat arches incident to the spread or open position of the blades.

The present invention is intended to provide a bucket or excavating device which will avoid such objectionable features of the ones heretofore in use and which will be more efficient in use.

The objects of this invention are to provide an improved excavating or digging bucket which is particularly adapted for use in connection with hard material, such as gravel or the like, or for lifting out boulders; to provide an excavating bucket having a relatively large number of blades whereby each of the blades may be comparatively narrow; to provide an excavating bucket having a plurality of blades which are pivoted so that the pivotal points come approximately over, or preferably within, the points, whereby the engagement of the points with the material to be excavated tends to open the blades or hold them in open position; to provide a multiple bladed excavating device having a supporting frame which encircles the blades or arms; to provide a multiple bladed excavating bucket having adjustable weights which are adapted to coact with the weight of the bucket to force the blades into the material; to provide a bucket having a plu-

rality of blades with closing means for the blades which includes toggle mechanism; and to provide such other improvements in construction and advantages in use as will appear from the following description.

In the accompanying drawings illustrating this invention

Figure 1 is a vertical sectional view with parts broken away or shown diagrammatically for convenience in illustration;

Figure 2 is a plan view also with parts broken away;

Figure 3 is a sectional view of one of the blades and arms taken on the line 3-3 of Figure 1; and

Figure 4 is a sectional view taken on the line 4-4 of Figure 2 showing one of the weights.

The bucket frame 5 is in the form of a ring and is preferably made octagonal as shown. It is provided at the corners or apexes with pairs of inwardly projecting lugs or bearings 6 for supporting the blades 7. These blades which are shown as being eight in number are comparatively long and narrow so that they each have relatively sharp digging points 8 which will tend to penetrate the material to be excavated. These blades are so shaped that they will close together to form a receptacle or bucket such as indicated in dotted lines in Figure 1.

These blades may be formed integrally with the arms 9 but are preferably secured thereto by means of bolts 10. These arms are preferably provided with flanges 11 to strengthen the same and to provide further support for the blades. The arms preferably project outwardly at approximately the upper ends of the blades, as shown at 12, to provide bearings which fit between the lugs 6 and which are pivoted thereto on pins 13. The arms 9 project upwardly beyond the bearings and are bent or curved inwardly at their upper ends, as shown at 14.

The upper end of these arms are connected

by links 15 with projections or bearings 16 on a central disk or plate 17. This disk or plate has upwardly extending bearings 18, carrying a pin or shaft 19 on which is mounted a pulley 20.

5 A headblock 21 is connected to the frame or ring 5 by means of arms or braces 22 which are bolted or otherwise secured to such members or which may be formed integrally therewith. These arms are preferably spaced intermediate of the blade supporting arms, as shown in Figure 2, in order to prevent any interference. The headblock 21 is provided with an eye 23 for attachment of the supporting cable (not shown).

10 One end of a closing cable 24 is secured to the block 21 as shown at 25. This cable passes down under the pulley 20 and then up through a hole 26 in the block 21. It will 15 be understood that these cables are manipulated in the usual manner for operating the bucket.

15 It will be seen that when the jaws are open and the bucket is supported on the points thereof, as when being driven into the material to be excavated, all of the weight or power of the frame 5, arms 22 and headblock 21 will be transmitted to the blades through the pivots 13 so that the tendency is to drive 20 the blades straight into the material without bending the same. This weight or force may be augmented by additional removable weights 27 which may be applied to the frame and secured thereto by means of screws 28, 25 as shown in Figure 4. It will also be noted that the points of the blades may, if desired, be curved slightly outwardly, as shown in Figure 1, so that the action of the material on the blades tends to hold them open or force 30 the lower ends slightly outwardly. It will also be noted that in the arrangement shown the pivot points 13, being below the upper ends of the blades, there will be some overlapping of the upper ends of the blades when 35 in open position.

40 In operation the bucket may be dropped to cause the blades to be forced into the material to be excavated and practically all of the force due to the weight of the frame and attached parts will be applied directly above 45 the points or in alignment with the blades so that the blades will be forced into the material with but little possibility of their yielding or being bent. When the closing cable is drawn up it raises the central disk 17 and causes the bucket arms to be forced outwardly at the top, as shown in dotted lines in Figure 1. The final closing action brings into effect the toggle action of the links 15 so 50 that there will be abundant closing power. The provision of a single pulley on the disk 14 will ordinarily be sufficient to give the desired closing action, but it will be observed that such block and tackle arrangement may 55 be modified by adding additional pulleys in

a well known manner if further force is desired.

60 My improved bucket is adapted for various uses such as excavating gravel or the like and is particularly useful in connection with excavating deep wells as for removing boulders or cutting through hard material. While the illustrations disclose a preferred form, it will be apparent that changes may be made in the construction without departing from the 65 scope of the invention as set forth in the following claims in which I claim:

70 1. In a bucket of the character set forth, the combination of a substantially octagonal open frame, bucket jaws pivoted in the angles of the frame, a headblock, connections between the headblock and the frame, a central operating member, means comprising arms secured to the jaws and links from the arms to said operating member for connecting said member with the jaws for opening and closing the same, and a cable coacting with said central operating member for actuating the same.

75 2. A bucket of the orange-peel type having eight relatively long narrow blades, arms secured to said blades and extending upwardly beyond the same, a frame member encircling the arms, pivotal connections between the arms and the frame member, a headblock, arms connecting the headblock with the frame member, a center disk, links connecting the disk with the upper ends of the respective arms, and a closing cable coacting with the headblock and with the center disk 80 for raising said disc to close the jaws.

85 3. In a bucket, the combination of a ring frame having inwardly projecting bearings, bucket arms pivoted to said bearings, blades secured to said arms, a central blade closing member, links connecting said member with the respective arms and adapted to provide a toggle action in the closing movement, a headblock, arms connecting the headblock with the frame, a pulley on said closing member, and a closing cable having one end secured to the headblock and passing under said pulley and up through an opening in said headblock.

90 4. The combination with a bucket of the character set forth having jaws with a frame member encircling the same to which said jaws are pivoted, of weights adapted to be secured to said frame member adjacent to the pivots.

95 5. In an excavating bucket, the combination of a headblock, means for securing a supporting cable to said headblock, a substantially octagonal frame member, arms connecting the block and frame member, bearings projecting inwardly from said frame member, arms pivoted to said bearings and having their upper ends curved inwardly, blades secured to said arms and adapted to form a bucket when in closed position, a cen- 100

tral disk member, links connecting said member with the upper ends of the arms, a pulley mounted on said member, and a closing cable passing through an opening in the headblock,
5 then under said pulley and having its end secured to the headblock, the arrangement being such that when the disk member is in lowered position the bucket will be open and when the disk member is in raised position
10 the bucket will be closed.
